UNITED STATES PATENT OFFICE.

FRANK REESE, OF MINNEAPOLIS, MINNESOTA, ASSIGNOR TO REESE METAL WEATHER STRIP CO., OF MINNEAPOLIS, MINNESOTA, A CORPORATION OF MINNESOTA.

WEATHER STRIP.

Application filed January 24, 1927. Serial No. 163,126.

My present invention relates to improvements in weather strips for sliding window sashes and, more particularly, to means for detachably securing the same to such sashes.

Generally stated, the invention consists of the novel devices and combinations of devices hereinafter described and defined in the claims.

It is well known that after sliding sashes have been provided with metallic weather strips, it is practically impossible to remove and replace such sashes for the purpose of glazing or otherwise repairing the same without bending or otherwise damaging the weather strips so that they are never as efficient as when originally installed.

By the use of my present invention, weather strips may be applied to window sashes and secured in such a manner as to permit easy removal of the sashes and the replacement thereof without damaging the weather strips, sashes, or window frame.

In the accompanying drawings, which illustrate the invention, like characters indicate like parts throughout the several views.

Referring to the drawings:

Fig. 1 is an inside elevation, with some parts broken away, of a window frame, in which are mounted upper and lower sliding sashes to which the invention is applied;

Fig. 2 is a fragmentary section taken horizontally through the frame and sashes, on an enlarged scale, with said sashes positioned at the same elevation; and

Fig. 3 is a fragmentary perspective view of one of the weather strips designated hereinafter as the sash member, and its retaining clip separated therefrom.

An upper sash 4 and a lower sash 5 are slidably mounted in a frame 6 having fixed outer stops 7 for said outer sash and removable inner stops 8 for said inner sash, held in position by nails or screws, not shown, and grooves 9 for parting or central stop strips 10.

These parting or central stop strips 10 are in the form of metallic channel bars, preferably formed from sheet metal and having parallel sides, removably mounted in the grooves 9 and held in position by wood screws 11. Said parting strips 10 extend from the top to the bottom of the window frame 6.

The sash members of the metallic weather

strips are applied to the inner faces of the 55 stiles of the upper sash 4, and to the outer faces of the stiles of the lower sash 5, and are bent to form laterally projecting anchoring flanges 12 and substantially rectangular folds 13. These folds 13 are thus provided 60 with parallel flat portions 14 and 15, between which the cooperating flanges of the parting strips 10 are engaged with sufficient friction to insure very tight joints.

The air-sealing anchoring flanges 12 on the right-hand sash members are permanently secured by nails 16 to the outer edges of the right-hand stiles of the sashes 4 and 5. The anchoring flanges 12 on the left-hand sash members are slidably mounted in metallic channel-retaining members 17 on the left-hand edges of the sashes 4 and 5. These members 17 have laterally projecting anchoring flanges 18 permanently secured by nails 19 to the left-hand stiles of said sashes. The retaining members 17 and their anchoring flanges 18 are mounted in rabbeted seats in the left-hand stiles of the sashes 4 and 5 so that their outer surfaces are flush with the outer surfaces of said stiles.

To secure the left-hand sash members to the sashes 4 and 5 for common sliding movement therewith, there are provided wide Z-shaped clips 20 detachably secured, one to each of said sashes. On large windows, it 85 might be desirable to use two clips 20 for each sash member. These clips 20 are bifurcated to afford wide flat prongs 22 which extend transversely of the sash members and into correspondingly formed pairs of apertures 23 formed in said sash members.

To remove the sashes 4 and 5 from a window frame 6, the left-hand stop 8 is first removed and then said sashes are positioned so that a screw-driver may be used to remove 95 the screw 21 holding the clip 20 on the outer side of the lower sash 5. After this screw 21 has been removed, the respective clip 20 is detached from the sash member by withdrawing its prongs 22 from the apertures 100 23 therein.

The lower sash 5 may then be swung angularly inward and removed from the window frame 6. At this point, note that the same construction might also be used on the 105 right-hand side of the sash, as shown on the left, in which case both right and left-hand inner stops 8 could be removed, the screws

21 and clips 22 removed from both right and left sides of the sash, and the lower sash 5 could then be drawn directly inward.

The screw 21 and clip 20 attached to the upper sash 4 are then removed. The sash member of the upper sash 4 is then drawn out of its retaining member 17 either from over the top or from below the bottom of the upper sash 4, or the said sash member 10 may be held stationary, at either the top or bottom of the window opening, and the upper sash 4 moved to the reverse position in the opening in order to detach said sash member from its retaining member 17. 15 Then, by removing the screws 11 holding the left-hand channel stop 10, the upper sash 4 may be removed from the window frame 6 by swinging the same angularly inward. It will thus be seen that the left-hand sash 20 members may be removed without danger of bending or otherwise damaging the same. During the removal of the sashes 4 and 5 from the window frame 6 by horizontal angular swinging movement, the right-hand sash 25 members are readily detached from the flanges of the engaged parting strip 10 without danger of bending or damaging these weather strips. After the sashes 4 and 5 have been glazed or otherwise repaired, or 30 sash cords renewed, they are replaced in the window frame in just the reverse order from that required to remove the same from said window frame.

For the purpose of making operations of 35 removal and replacement of sashes clear, I have shown this mechanical method applied on weather strip construction as disclosed in my Patent No. 1,600,737, granted to me of date September 21, 1926. However, it is not 40 to be considered as limited only to this particular construction. The channel stop 10 may be considered the jamb member of any two-member equipment, and the weather strip the sash member of said two-member 45 equipment. The retainer strip 17 might be entirely eliminated, as it serves only as a seating strip for the flanges 12 of said sash members. If the location of these flanges were changed somewhat, a groove cut in the sash 50 would serve the same purpose as the retain-

er strip 17. Likewise, the clips 20 could also be eliminated by extending a flange from the said sash member and inserting screws or other fastening devices directly through said flanges. Thus, it will be seen that my invention is not limited only to the construction shown but may be applied to a variety of weather strip constructions, wherein two or more interlocking or engaging parts are used at the sides of the sashes. 60

What I claim is:

1. The combination with a window frame and sashes slidably mounted therein, of weather strips consisting of a stationary member attached to the frame and sliding members attached to the sashes, said sash member having laterally projecting air-sealing flanges seated in the sashes, and fastening clips at accessible portions of said sashes releasably holding the sliding members for 70 common movement with the sashes. 65

2. The combination with a window frame and upper and lower sashes slidably mounted therein, of weather strips at one side of the frame consisting of a stationary member 75 attached to the frame and sliding members attached to each of the sashes, said stationary member being in the form of a channel and affording a central parting strip for the sashes, said sliding members being applied so to the opposing faces of the sashes and having laterally projecting air-sealing flanges removably mounted in the sashes, said sliding members having interlocking sliding engagement with the flanges of the frame member and separable therefrom only by movement substantially at right angles to the plane of the sashes, and fastening means at accessible portions of the sashes attaching the sliding members thereto for common 90 sliding movement therewith. 85

3. The structure defined in claim 2 in which the lower sash is removable from its sliding member by a lateral movement to withdraw its air-sealing flange from the sash and in which the upper sash is removable from its sliding member by a sliding movement of the one in respect to the other. 95

In testimony whereof I affix my signature.
FRANK REESE.
